UNITED STATES PATENT OFFICE.

HEISTER S. HUNTER AND THOMAS WATKINS, OF PHILADELPHIA, PENNSYLVANIA.

WATER-GAGE.

1,218,661.

Specification of Letters Patent. Patented Mar. 13, 1917.

Application filed January 13, 1916. Serial No. 71,829.

To all whom it may concern:

Be it known that we, HEISTER S. HUNTER and THOMAS WATKINS, citizens of the United States, residing at Philadelphia, in the county of Philadelphia and State of Pennsylvania, have invented certain new and useful Improvements in Water-Gages, of which the following is a specification.

The principal object of the present invention is to simplify the construction and specific arrangement of water-gages now in general use with a view to enhancing the commercial value thereof. A further object of the present invention is to provide a water-gage so constructed that safety in its use is emphasized and wherein the probability of the reflex glass thereof breaking and the fractured particles scattered free of the gage parts, with consequent escape of steam, is reduced to a minimum. A further object of the present invention is to provide a water-gage wherein the necessity for the employment of usual packings is obviated. Other and further objects of the present invention reside in the providing of general details of construction and in the providing of specific arrangement, combination and connection of parts as will hereinafter appear.

30 The invention consists of the improvements hereinafter described and finally claimed.

The nature, characteristic features and scope of the invention will be more fully understood from the following description taken in connection with the accompanying drawings forming part hereof and in which:

Figure 1, is a front or face view of the water-gage.

40 Fig. 2, is a view in vertical section taken at right angles to Fig. 1.

Fig. 3, is a view in cross section, taken upon the line 3—3 of Fig. 2, and drawn to an enlarged scale.

45 Fig. 4, is a view in plan of the inner face of one of the removable caps.

Fig. 5, is a face view of the gasket.

Fig. 6, is a similar view of the reflex-glass.

50 Fig. 7, is a similar view of the backing element.

Fig. 8, is a top or plan view thereof, and

Fig. 9, is a view in side elevation of the backing element.

55 Referring to the drawings, there is disclosed a physical embodiment of the invention designed in a mode best known to us at

this time for practising the same. Obviously details of construction may be varied without departing from the fair spirit and scope 60 of the appended claims. In the specific embodiment disclosed 10, designates an elongated tube-like integral body or casing, the front and sides of which are substantially flat and the rear thereof generally curved. 65 In other words considered in cross-section, the casing 10, is substantially D-shaped, see Fig. 3. Top and bottom the casing 10, is enlarged and annular and is tapped as at 11, each tapped portion being of a diameter 70 at least equaling the body diameter. The tapped portions receive caps 12, and 13, which caps in turn are tapped to receive coupling pipes 14, and 15. The inner faces of the caps are counter-sunk as at 16, and 75 are centrally apertured in register with the pipes 14, and 15. The front face of the casing 10, has therein an elongated slot or sight opening 17, through which a reading of the gage may be had. The enlarged annular ends of the casing 10, at the rear thereof, are provided with squared offsets 18, 80 tapped to receive set screws 19, for a purpose to presently appear. Within the body 10, are located a flat gasket 20, of lead, a 85 reflex glass 21, and a backing element 22, of brass. The flat gasket 20, is fitted against the flat inner integral face of the body 10, and covers the same. The reflex glass 21, abuts against the gasket and in practice is 90 assembled so that in width or thickness, it does not project beyond the vertical medial line of the water gage. Abutting against the reflex glass is the backing element 22. In cross-section, this backing element is of 95 C-shape, or in other words, it is semi-tube like in contour. It is disposed within the casing so that the edges 23, thereof impinge against the reflex glass 21. With these parts in abutting position, assembled as 100 shown in the drawings, there is present a central continuous vertical passage formed immediately between the scored face of the reflex glass and the grooved face of the backing element and in alinement with the openings through the caps. The parts 20, 21 and 22 are maintained in this position and forced against the flat face of the body 10, by means of the set screws 19, which impinge against the curved outer wall of the backing element, jam nuts 24, being employed to prevent accidental displacement thereof. In this connection it is to be observed that the face of the casing 10, is an integral part, in 110

contradistinction to being a removable face. The lead gasket and reflex glass are positioned in abutting relation against such face and steam pressure which may be present 5 within the water-gage is directly back of the reflex-glass with the result that pressure upon said glass is evenly distributed over the entire inner surface thereof. Consequently as there is no strain exerted upon the outer 10 face of said glass, as by set screws or the like, the probability of the glass being fractured is reduced to a minimum. Even should said glass become fractured, such fractured parts will not be scattered free of 15 the body or casing, with consequent blowing out of steam, because no strain is present upon the outer face of the glass and an even pressure is maintained upon the inner face of the glass. By reason of the removable caps an unobstructed central opening 20 is present through the casing 10, whereby the gasket, glass and backing element in their relative abutting positions may be readily placed within the casing and secured to place by the set screws 19. In 25 this connection, it is to be noted that said gasket, glass and backing element are of the same height and extend throughout substantially the entire height of the casing 10. 30 The grooved face of the backing element top and bottom is recessed as at 25, in order to provide an enlarged upper and lower mouth for the central passage before described. The flat gasket of lead forms a relatively 35 yielding member which lends itself to any irregularities of the body-face or reflex glass, so that when the set screws are adjusted to place a steam and water tight joint is effected between said parts, thus obviating numerous packings. It is to be noted in 40 this respect that a shroud for the reflex glass is not required. By having the central continuous passage directly back of the reflex glass, the latter is maintained free of sediment or deposits, so that a clear reading of 45 the gage may be had.

What we claim is:

1. A water-gage embracing an elongated integral continuous body having a central 50 passage therethrough, the central portion of which body is contracted and the ends of which are enlarged and internally screw-threaded, the diameter of each threaded portion being at least equal to diameter of said 55 central passage, said body having a flat front face provided with a sight opening and having tapped portions upon the body back, removable caps each having an opening there- 60 through for partially closing the open ends 65 of said body, a flat gasket within the body for covering the flat inner surface of the body face, a reflex-glass fitted against said gasket, a backing element of semi-tube con-

tour disposed within the body to form a continuous vertical passage directly to the 65 rear of said glass and in alinement with the cap openings, and set screws operative through the tapped rear of said body engaging the backing element to force said element, glass and gasket bodily against the 70 face of the body.

2. A water-gage embracing an elongated integral continuous body having a central passage therethrough, the central portion of which body is contracted and the ends of 75 which are enlarged and internally screw-threaded, the diameter of each threaded portion being at least equal to diameter of said central passage, said body having a flat front face provided with a sight opening and having tapped portions upon the body back, caps each having an opening therethrough for partially closing said open ends, a gasket of yielding metal within the body for 80 covering the flat inner surface of the body 85 face, a reflex-glass fitted against said gasket, a backing element of C-shape disposed within the body to form a continuous vertical passage directly to the rear of said glass and in alinement with the cap openings, and set 90 screws operative through the tapped rear of said body for engaging the curved rear face of said backing element to force said element, glass and gasket bodily against the 95 face of said body.

3. A water-gage embracing an elongated integral continuous body, the central portion of which is contracted and of D-shaped cross-section and the enlarged ends of which are of circular cross-section internally 100 tapped to receive caps, said tapped portions being of a diameter at least equal to the diameter of said body central portion, said body having a flat front face having a sight opening, caps each having an opening there- 105 through for partially closing said open ends, a gasket of yielding metal within the body for covering the flat inner surface of the body face, a reflex glass fitted to said gasket, a backing element of C-shape disposed within 110 the body to form a continuous, vertical passage directly back of said glass and in alinement with the cap openings, tapped off-set portions for the body adjacent the ends thereof and set screws operative through 115 said off-sets for engaging the curved rear face of said backing element to force the backing element, glass and gasket bodily against the face of said body.

In testimony whereof, we have hereunto 120 signed our names.

HEISTER S. HUNTER.
THOMAS WATKINS.
